UNITED STATES PATENT OFFICE.

ISAAC E. MERRITT, OF LOCKPORT, NEW YORK.

MOWING-MACHINE.

SPECIFICATION forming part of Letters Patent No. 233,426, dated October 19, 1880.

Application filed June 3, 1880. (Model.)

To all whom it may concern:

Be it known that I, ISAAC E. MERRITT, of Lockport, in the county of Niagara and State of New York, have invented certain new and useful Improvements in Mowing-Machines; and I do hereby declare that the following description of my said invention, taken in connection with the accompanying sheets of drawings, forms a full, clear, and exact specification, which will enable others skilled in the art to which it appertains to make and use the same.

This invention has general reference to mowing-machines; and it consists, essentially, in the novel combination of parts and details of construction, as hereinafter first fully set forth and described, and then pointed out in the claims.

In the drawings already referred to, which serve to illustrate my said invention more fully, Figure 1 is a plan of my improved mowing-machine. Fig. 2 is a sectional elevation in line *x x* of Fig. 1. Fig. 3 is a side elevation, one wheel of the machine being removed. Fig. 4 is an elevation of the shoe and push-bar. Fig. 5 is a section in line *y y* of Fig. 3. Fig. 6 is a side elevation of the mechanism actuating the pivoted end of the connecting-bar.

Like parts are designated by corresponding letters of reference in all the figures.

The object of my present invention is the production of a mower possessing the following peculiarities and advantages, viz: First, a ground-wheel capable of being adjusted with reference to the height of cutting without removing a single bolt or screw, and without stopping the machine for a single moment; second, a knife-bar that can be rocked on a longitudinal axis and raised and lowered on either the inner or outer end by the operator of the machine while going over the field. To attain these, as well as other important results hereinafter more fully set forth, I construct my mower, essentially, of a frame or platform, A, having across its rear end the usual axle, B, serving as a means of locomotion, in conjunction with a pair of wheels, C C', and to give motion to the usual cutter-bar (not shown) by means of suitable gearing in- closed in the dust-boxes D D', operating upon a shaft, E, having on its forward end a crank-

disk, F, provided with a pitman, H, connected to said crank-disk at G in the usual manner to vibrate the knife-bar when the machine is moving in a forward direction.

55

The front end of the platform A terminates in a lug, A', within which revolves a shaft, I, of the chain-wheel I', said shaft being provided with a universal joint, J, on the end opposite the chain-wheel I'. This latter wheel is connected with another chain-wheel, K, by means of an endless belt, L, said chain-wheel K being operated by means of a lever, M, having a catch, m, engaging a notched segment, N, secured to or formed in one piece with said platform A.

With the universal joint J is connected a curved rod or shaft, O, passing through a casing, P, into, and forming the axle for, the ground-wheel Q. This casing P consists of a dished plate having a curved slot, a, the dished part of said casing being occupied by a cam-plate, R, Fig. 5, having a hollow boss, R', serving as a bearing for the shaft O. Upon the end of said shaft O is placed a sleeve, O', upon which revolves the ground-wheel Q, there being formed on the end of said shaft O an angular section, upon which is placed a washer, O'', having a square aperture, so as to prevent the nut O''', holding the sleeve and washer to the axle, from working loose. The boss R' on the plate R is placed out of the center of said plate a distance corresponding with the semicircular aperture a in the dished plate P, so that by revolving said shaft O it is made to also revolve the plate R, and thereby to move in the curved slot a up or down, the object of which will hereinafter be mentioned.

On the lower side of the platform A is provided a bracket, S', Fig. 3, to which is pivoted a push-bar, T, the forward end of which is pivoted to a collar or box, T', having two lugs, b b', through which the bolt c, Fig. 4, passes. One of these lugs, b', is formed into an arm, b'', which is connected with a sector, d, Fig. 1, by means of a chain, e. On the under side of the box T' is provided a cam, f, acting upon the shoe V in a manner farther on specified.

The box T' is placed around near the forward end of a curved connecting-bar, U, the extremity of which is downwardly bent at U' to connect with two lugs, g g', on the shoe V.

The opposite extremity of this connecting-bar is pivoted to a double eye or fork, *h*, Figs. 3 and 6, on the lower end or short arm of a lever, *X*, pivoted in a slot in the platform *A*. The 5 upper end of this lever is provided with a slot, *i*, in which engages the pivot *i'* of a connecting-rod, *j*, the opposite end of which rod connects with a foot-lever or treadle, *Y*, pivoted to the platform *A* in any suitable manner. 10 The relative position of the pivots of this lever *Y*, the lever *X*, and the connecting-rod *j* is such that when said lever *Y* is depressed, as shown in Fig. 6, the connecting-rod will, with point of connection with said lever, be below 15 a line drawn from the pivot *i'* to the pivot *i''* or fulcrum of said lever, whereby the lever cannot be lifted upward by any endwise pressure brought to bear upon it by said connecting-rod until it is lifted by the operator sufficiently to bring said point above said line. 20 In this manner the treadle is positively locked when depressed. Other devices or mechanism may, however, be provided for locking said treadle without changing the nature of my invention. 25

As hereinbefore described, the lever *b''* on the box around the connecting-bar *U* is connected with the chain-pulley *d* by a chain, *e*. This chain-pulley is fixed to or formed in one 30 piece with a ratchet-wheel, *Z*, to which, in turn, is affixed a hand-lever, *Z'*, by means of which said ratchet-wheel is operated.

To the frame *A* is pivoted a pawl, *Z''*, the forward end or catch, *n*, of which engages the 35 teeth of said ratchet-wheel, so as to retain the latter in any desired position. By means of this hand-lever *Z'* the lever *b''* on the box *T'* is raised or lowered by the mechanism described, and this raising and lowering of said 40 lever has the effect of oscillating the box *T'* on the connecting-bar *U*, and, by means of the cam *f*, of depressing that end of the shoe *V* directly underneath said cam, and thereby to lift the outer end of the finger-bar *B*.

45 On the forward end of the shoe *V* is provided a perforated lug, *V'*, through which is passed the tapering shank *R''* on the casing *P*, (see Fig. 5,) thereby forming a journal for said casing to oscillate upon.

50 The construction of the shoe *V*, as well as that of the knife and finger bars, knife-bar head, and its connection with the connecting-rod *H*, does not differ materially from that of other machines, and I therefore do not deem it necessary to enter into a detailed description thereof.

55 In operation, suppose it to be desired to raise or lower the cutting and finger bars for a close or a high cut, or for raising in passing over 60 very loose soil, where the cutting needs to be done high to prevent the stalks being pulled up, or in going from clover-fields to cutting barley, which latter, also, should be cut high, nothing need be done but to actuate the lever *M* in the proper direction. This will cause the chain-wheels *K* and *I'* to partly revolve,

and by also revolving the shaft *O* and turning the disk *R* in the casing *P* to raise or lower the shoe *V* with the finger and knife bars. Again, supposing it to be desired to pass an 70 obstruction near the machine or on the inner side of the finger-bar. In this case the handle *Z'* is actuated so as to raise the shoe *V* by the lever *b''* and cam *f*, acting upon said shoe, while to raise the outer end of the finger-bar 75 the foot-lever *Y* is depressed. This latter operation will throw the lever *X* forward and the connecting-bar at its fulcrum at *h* rearward. This connecting-bar *U*, being curved somewhat like the letter **S**, is in itself a lever, so that by 80 throwing said lever *X* rearward said connecting-bar will slightly revolve within the box *T'*, and thus tilt upward the outer end of the finger-bar, the inner end not being lifted on account of the shoe *V* remaining in its original 85 position. When the connecting-bar is thus thrown backward at *h* the entire finger-bar may, however, be lifted from the ground by actuating the handle *Z'* in the proper direction to pull the shoe up by the chain *e*. 90

To carry the finger and knife bars to and from the field, the outer ends of the said bars are lifted up around their fulcrum, (the bolt passing through the lugs *g g'* on the shoe *V*,) and turned over to rest either on the pole *A'''* 95 or upon any other proper support. (Not shown.)

It is a fact that when the foot-lever *Y* is depressed and the lever *X* thereby thrown forward, the points of the fingers go down and the rear side of the finger-bar up, so that in 100 backing, said finger-bar will readily pass over the ground and over obstructions without fear of being caught. It is further a fact that in this machine the ground-wheel *Q* always rests upon the ground, even when the points of the 105 fingers are raised, which is not the case in any other machine with which I am acquainted. So may the points of the fingers be raised by the action of the foot-lever and its accessories, and yet carry the said finger-bar upon both 110 the driving and grain wheel, (not shown,) a feature which, in going over mowed ground, and for other obvious reasons, is very desirable, since the finger-bar need not be raised entirely off the ground. 115

Having thus fully described my invention, I claim as new and desire to secure to me by Letters Patent of the United States—

1. In a mowing-machine, the devices for raising and lowering the finger-bar consisting of 120 the shoe *V*, casing *P*, eccentric *R*, ground-wheel *Q*, rod *O*, and mechanism for rotating said rod, substantially as set forth.

2. In a mowing-machine, the combination, with the slotted casing *P*, of the eccentric *R*, 125 rod *O*, ground-wheel *Q*, universal joint *J*, wheels *I'* and *K*, and band *L*, as and for the purpose set forth.

3. The combination, with the shoe *V*, having the lug *V'*, of the pivoted casing *P*, having 130 the curved slot *a*, the eccentric disk *R*, provided with perforated boss *R'*, the shaft *O*,

sleeve O', and ground-wheel Q, substantially as set forth.

4. The combination of S-shaped connecting-bar U with lever X, box T', provided with a cam, the finger-bar, and operating devices, substantially as set forth.

5. The box T', having the lever b" and cam f, in combination with the bar U, push-bar T, and shoe V, pivoted to said bar U, as and for the purpose set forth.

6. The combination, with the bar U, of the lever X, having the fork h and a slot, i, the

rod J, and foot-lever Y, for oscillating said connecting-bar, as specified, the parts being constructed and arranged, in relation to one another, substantially as set forth. 15

In testimony that I claim the foregoing as my invention I have hereto set my hand in the presence of two subscribing witnesses.

ISAAC E. MERRITT.
